UNITED STATES PATENT OFFICE.

CHARLES A. KUENZEL, OF BUENA VISTA, COLORADO.

GAS-GENERATOR.

1,039,549.

Specification of Letters Patent. Patented Sept. 24, 1912.

Application filed August 26, 1911. Serial No. 446,252.

To all whom it may concern:

Be it known that I, CHARLES A. KUENZEL, a citizen of the United States, residing at Buena Vista, county of Chaffee, State of Colorado, have invented a new and useful Gas-Generator, of which the following is a specification.

My invention consists of an improved apparatus for producing gas from liquid hydrocarbon for burning in furnaces of various kinds.

It further consists of such apparatus which is capable of being applied to existing furnaces without any radical changes in their structure.

It further consists of such apparatus in which air under pressure and liquid fuel are injected and mixed in a retort heated from the furnace and thereupon mixed with air under pressure heated in a separate retort, all in a finely comminuted state.

It further consists of such apparatus comprising an atomizer for mixing liquid fuel and air under pressure, a retort heated from the furnace for heating and vaporizing such mixture, a means for heating air under pressure, a mixing and comminuting device for mixing such vapor and air, a superheating retort for the mixture thus produced, and a heated expansion and distributing chamber from which the gas passes to the burners.

It further consists of other novel features of construction, all as will be hereinafter fully set forth.

The invention is satisfactorily illustrated in the accompanying drawings, but the important instrumentalities thereof may be varied, and so it is to be understood that the invention is not limited to the specific arrangement and organization shown and described.

Figure 1 represents a front elevation of one of a battery of steam boilers provided with my improved gas-generating apparatus. Fig. 2 represents a longitudinal vertical section of the heating, atomizing and mingling elements of the apparatus. Fig. 3 represents a longitudinal sectional detail view of the atomizing and mingling cylinder. Fig. 4 represents a face view of the inner portion of the air and vapor heater. Figs. 5 and 6 represent sectional detail views respectively of the discharging and receiving ends of one of the atomizing and mingling tubes. Figs. 7, 8 and 9 represent respectively transverse sections of the air and

vapor heater on the lines $x-x$, $y-y$, and $z-z$ in Fig. 2.

Similar numerals of reference indicate corresponding parts in the figures.

Referring to the annexed drawings, the numeral 1 designates the front wall of a steam boiler, the furnace of which has the usual ash-pit closed by doors 2. The door opening of the boiler furnace is closed by a retort structure 3, extending into the furnace sufficiently to be heated by the heat therein. An oil tank 4, is provided below the level of the furnace, for containing the liquid fuel, crude oil, gasoline, refined oil, or whatever liquid hydrocarbon may be employed, and said tank has a connection 5, from a compressed air tank 6, to provide pressure upon the surface of its liquid contents. The air pressure is derived from an air-compressor, 7, of any suitable or desired construction, the engine of which is in the present instance fed from a steam pipe 8, leading from the boiler. The liquid hydrocarbon is fed from the tank through a pipe 9 extending to the bottom of the same, under pressure, to an injector device or atomizer 10, entering the retort structure at one side of the same and near its upper edge. The retort structure consists of a retort casting 11 having four horizontal ducts or chambers 12, 13, 14 and 15, an inner plate 16 forming a space filled by a packing 17, of asbestos or similar material, and a face plate 18 forming an expansion chamber 19, between it and the retort casting. The non-conducting packing has cold air ducts 20 through it, which open through the inner plate to provide air for the furnace. The injector 10 has the oil pipe 9 extended by a nozzle 21, which is axial within an air-duct 22 supplied with compressed air by a pipe 23, branching from a pipe 24, leading from the compressed air tank. The nozzle and air duct extend through the face plate and the retort casting into the upper transverse retort chamber or vaporizing chamber 12, so that the spray of mixed air and fuel will be further vaporized and dried. At the opposite end of the retort chamber, a vapor pipe 25 is connected, which leads to an annular channel 26 in a cap 27 of a comminuting and mixing casing 28, preferably cylindrical. Said cap has a domed interior which communicates through a neck 29, with a passage 45 and openings 46, with the superheating retort chamber 14.

The main casing 28 has heads 30 and 31 at its ends, and a number of copper pipes 32, have their ends supported in said heads, having tapering nozzles 33 screwed upon the ends pointed toward the retort structure and funnel-shaped nipples 34, at their other ends, said nozzles and nipples also serving to draw the two heads of the main casing together. A series of longitudinal copper tubes 35 extend from the annular channel 26 and through the main casing to the opposite end of the same, where they enter an annular chamber 36, in a cap 37 secured at that end of the main casing. A perforated mixing-plate 38 is supported in the chamber, near the funnel-shaped nipples of the pipes, and a domed and perforated comminuting plate 39 is also supported within the chamber in the cap. A pipe 40 leads from the compressed air pipe 24 and enters one end of the air-heating chamber 13, and a pipe 41 leads from the opposite end of the chamber and opens into the upper side of the main casing. A pipe 42 opens from the opposite side of the main casing and extends around to the outer cap of the same, through which it enters. The superheating retort chamber communicates with the expansion chamber through an inclined passage 43, and said chamber communicates with the lowermost retort-chamber 15, from which a number of burner-tubes 44 open into the furnace.

To start the apparatus, it is necessary to build a fire in the ash-pit of the furnace to heat the retort structure. When the retort structure is sufficiently heated to volatilize the hydrocarbon, compressed air is admitted on top of the fuel in the tank from the compressed air tank and to the several air pipes. The compressed air will produce a spray or jet of finely comminuted liquid which will mix with the air and vaporize in the upper vaporization retort-chamber 12, whence such vapor will pass to the annular chamber 26 of the structure comminuting and mixing through the outer series of pipes in the casing to the domed chamber at the end of the casing. Air has in the meanwhile been forced through the air heating chamber, where it has been heated and has been carried to the interior of the main casing where it heats the longitudinal pipes and passes through the pipe 42 to the mingling chamber at the end of the casing, passing through the domed comminuting plate and being broken up in streams which meet the vaporized fuel and air and mingle therewith, passing through the flat perforated mixer plate and into the funnel shaped ends of the inner series of copper pipes, through which the mixture passes, being retained at high temperature by the hot air passing through the main casing. The gas mixture issues in fine jets through the nozzles at the ends

of the pipes, into the domed chamber and thence through the neck passages and openings into the superheating retort-chamber, and from there, through the inclined passage into the lower manifold retort-chamber where it is distributed to the burners and is ignited and consumed in the furnace, where the gas fire will now heat the retort structure.

By heating and vaporizing mixed oil and air, separately heating air and mixing that with the gas thus produced, superheating the mixed gas and air and thereby practically fixing such gas-mixture, and finally burning such superheated gas, complete combustion and intense heat is obtained. A very intimate gas-mixture is obtained by passing the heated air through the domed and perforated comminuting plate into the chamber within it, into which the heated and vaporized fuel and air mixture is introduced through the narrow annular slot 47 leading from the annular chamber or channel 36. This slot causes the heated vapor to issue in a thin annular sheet which is struck by the converging streams of heated air passing through the perforations of the domed comminuting plate, whereupon the mixed gas and vapor is still further broken up and more intimately mixed by passing through the flat mixer plate 38 and the copper pipes 32. The gas-mixture is prevented from losing heat when passing through these pipes by the hot air surrounding them in the main casing, and the fine jets of the gas-mixture emanating from the nozzles 33 will be still more intimately blended by striking the concave inner wall of the cap 27, and will be converged into the neck 29, which conveys the mixture into the superheating retort-chamber, whence the mixture passes into the manifold retort-chamber, from which it issues through the burner tubes.

A thorough disintegration and blending of the component elements of the fuel and air is attained in this apparatus and the gas and air mixture is kept continuously heated, so that there can be no possibility of the mixture condensing before ignition and consumption of the same.

The gas and air mixture produced in my apparatus is thoroughly blended and fully oxygenated so that the mixture will be fully consumed without smoke or other signs of carbonization.

The retort casting is protected by the asbestos filling or packing to prevent it from being burned or warped from the intense heat generated from the burners.

The copper tubes 32 may be renewed in the case one or more tubes burst or wear out, by removing the caps of the main casing, unscrewing the nozzle and nipple at the ends of the injured tube, and withdrawing the

tube, which is held in place by such nozzle and nipple with no other fastening, and a new tube may then be inserted and secured by the nipple and nozzle.

5. All parts of the apparatus are easily accessible for cleaning and repair.

The apparatus is capable of adaption to boiler furnaces, either stationary or employed in locomotives and steamships, or 10 to smelting and metallurgical furnaces or to any furnace where liquid hydrocarbon fuel is employed. As no smoke is generated and no cinders are ejected from the stack, this apparatus is of great advantage when 15 used in a locomotive boiler furnace and in a steamboat boiler furnace.

Having thus described my invention, what I claim as new and desire to secure by Letters Patent, is:—

20 1. In a gas generator for a furnace, a vaporizing retort heated by the furnace, an atomizer discharging into such retort and having means for supplying air and liquid fuel under pressure, a chamber heated by the furnace and having means for supplying it with air under pressure, and a comminuting and mixing device having a plurality of restricted passages and connected to said retort and chamber.

30 2. In a gas generator for a furnace, a vaporizing retort, an atomizer discharging into said retort and having means for supplying it with oil and air under pressure, a chamber having means for supplying it with air under pressure, a comminuting and mixing device connected to said retort and chamber, a superheating retort connected to the discharge from said device, and a distributing retort communicating with said 35 superheating retort and having burners, said retorts constructed to be supported in the fire-door opening of a furnace to be heated from the same and have the burners project into the same.

45 3. In a gas generator for a furnace, an atomizer for atomizing and mingling air under pressure and liquid hydrocarbon, a retort heated by the furnace and having the atomizer discharging into it to vaporize the 50 mixture produced, a chamber having means for supplying air under pressure to it and heated by the furnace, a comminuting and mixing device having a plurality of restricted passages and connected to the vapor 55 retort and air chamber, a superheating retort connected to the discharge end of said comminuting and mixing means and heated by the furnace, and burners communicating with said last retort.

4. In a gas generator for a furnace, a 60 retort-structure comprising a retort casting formed with a transverse vaporizing chamber, transverse air heating, superheating and distributing retort chambers, a face plate having passages communicating with said 65 chambers, an inner plate secured to the casting and spaced therefrom, and a filling of non-heat conducting material in said space, said retort structure being adapted to be supported in the fire-door opening of a 70 furnace in combination with means for connecting said chambers with each other.

5. In an apparatus of the character stated, a comminuting and mixing device comprising a casing having an inlet and an outlet, a cap at one end of said casing formed with an annular channel connected to receive heated oil vapor and air and with a domed chamber having a discharge neck, a domed cap at the opposite end of the casing formed 80 with an annular channel having a narrow annular slot opening into the interior of said cap, a domed and perforated comminuting plate within the cap, a flat perforated mixer plate in the cap, heads at the ends of the 85 casing, tubes connecting the annular channels in the caps, tubes supported at their ends in the heads, and a pipe connection from the outlet of the casing to the domed 90 cap.

6. In an apparatus of the character stated, a casing, heads at the opposed open ends of said casing, tubes having their ends fitted through said heads, tapering nozzles screwed upon the discharge ends of said tubes and 95 funnel-shaped nipples screwed upon the receiving ends of said tubes.

7. In an apparatus of the character stated, a casing having a series of comminuting and mixing tubes through it, an annular 100 closed channel at one end of such casing and having an interior annular and narrow slot, means for admitting a heated mixture of hydrocarbon vapor and air to said channel, a cap closing the end of said casing and 105 having means for admitting heated air through it, a domed and perforated comminuting plate within said cap to discharge converging streams of heated air to the annular sheet of vapor issuing from the annular slot, and a perforated mixing plate in the cap and admitting gas through it to the ends of the tubes.
